US0D1079213S

(12) **United States Design Patent** (10) **Patent No.:** **US D1,079,213 S**
(45) **Date of Patent:** **** Jun. 17, 2025**

(54) **SHOE**

(71) Applicant: **TYR Sport, Inc.**, Farmingdale, NY (US)

(72) Inventors: **Matthew Vito DiLorenzo**, Farmingdale, NY (US); **Yang Wang**, Farmingdale, NY (US); **Stephanie Lawrence**, Farmingdale, NY (US); **Corey Berger**, Farmingdale, NY (US)

(73) Assignee: **TYR SPORT, INC.**, Farmingdale, NY (US)

(**) Term: **15 Years**

(21) Appl. No.: **29/833,887**

(22) Filed: **Apr. 7, 2022**

(51) LOC (15) Cl. **02-04**

(52) U.S. Cl.

USPC **D2/947**; D2/951; D2/953; D2/958

(58) **Field of Classification Search**

USPC D2/896, 900, 902, 907, 908, 925, 946, D2/947, 948, 949, 950, 951, 952, 953, D2/954, 955, 956, 957, 958, 959, 960, D2/961, 964, 972, 973, 974, 976, 977

CPC A43B 3/244; A43B 3/246; A43B 5/00; A43B 5/06; A43B 5/10

See application file for complete search history.

(57) **CLAIM**

The ornamental design for a shoe as shown and described.

DESCRIPTION

FIG. 1 is a perspective view of the shoe of the present invention showing our new design;

FIG. 2 is a right side view thereof;

FIG. 3 is a left side view thereof;

FIG. 4 is a rear view thereof;

FIG. 5 is a front view thereof;

FIG. 6 is a top view thereof; and,

FIG. 7 is a bottom view thereof.

The broken lines depicted in the figures form no part of the claimed design.

1 Claim, 3 Drawing Sheets
